THE NORRIS PETERS CO., PHOTO-LITHO., WASHINGTON, D. C.

UNITED STATES PATENT OFFICE.

HARMON S. PALMER, OF WASHINGTON, DISTRICT OF COLUMBIA, ASSIGNOR OF ONE-HALF TO CLYDE PALMER, OF WASHINGTON, DISTRICT OF COLUMBIA.

TOY BUILDING-BLOCKS.

1,274,353.

Specification of Letters Patent.

Patented July 30, 1918.

Application filed June 8, 1916. Serial No. 102,529.

To all whom it may concern:

Be it known that I, HARMON S. PALMER, a citizen of the United States, residing at Washington, in the District of Columbia, have invented new and useful Toy Building-Blocks, of which the following is a specification.

The present invention appertains to toy building blocks, and it is the object of the invention to provide toy building blocks by means of which children can build toy houses, forts and other buildings or structures of various configurations, whereby to amuse and instruct the children.

15 It is the object of the invention to provide building blocks of different sizes, but all constructed according to a certain unit of measurement, whereby structures of various sizes and shapes can be built up from the various 20 blocks, and whereby windows, doors and other openings can be provided for.

The invention includes novel means for securing together the various courses of blocks, so that the building or structure will 25 be substantial.

The invention also makes provision in a simple and effective manner for windows, doors, and the like, at various points of the building construction, so that with a suitable 30 supply of the blocks and accompanying parts, a child can construct innumerable forms, sizes and styles of toy structures, which will not only be amusing but which will also be instructive along architectural 35 and building lines.

It is also within the scope of the invention to provide toy building blocks and accompanying building material which can be produced at a small cost, so as to be put on sale 40 at a nominal price, and by means of which the desired objects are carried out.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within 45 the scope of what is claimed without departing from the spirit of the invention.

The invention is illustrated in the accompanying drawings, wherein:—

Figure 1 is a front view of a building built 50 up from the present blocks.

Fig. 2 is a horizontal section on the line 2—2 of Fig. 1.

Fig. 3 is a vertical section on the line 3—3 of Fig. 2.

Figs. 4, 5 and 6 are perspective views of 60 different blocks which are used.

Fig. 7 is a perspective view of one of the window panes or panels.

Fig. 8 is a perspective view of a pair of dowel pins showing the joint therebetween, 65 portions being broken away.

Fig. 9 is a perspective view of another style of dowel pin.

Fig. 10 is a fragmental horizontal section 70 wherein the dowel pins are disclosed in different positions from those which they occupy in Fig. 2.

The blocks and accompanying parts are preferably provided or sold in sets, which may contain different numbers of parts to be 75 sold at different prices, and each set contains toy building blocks of different sizes. There are plain blocks 1 of different lengths, but all of the same height and width, and the lengths thereof being according to a standard unit of measurement, say one-half of an inch. The blocks 1 can therefore be of different lengths, varied by one-half inch, so that blocks one-half inch in length, one inch in length, one and one-half inches in length, 80 and so on, can be used to meet the various conditions which arise in building the various structures. Each of the blocks 1, except the shortest thereof, as seen in Fig. 5, is provided with square openings 2 extending vertically therethrough and arranged in a longitudinal series, said openings being spaced in accordance with the unit of measurement. The ends of each block 1 have recesses or "half" openings 3, which when they match 85 with the recesses of the adjacent blocks, will provide openings to register with the openings of the corresponding upper and lower blocks of the adjacent courses. Corner blocks 4 are also provided, which may be of 90 different sizes, as will be evident from the foregoing, and each block 4 is provided with square vertical openings 5 extending therethrough and arranged in accordance with the unit of measurement. The ends of the 95 block 4 have recesses or "half" openings 6

the same as the blocks 1. The corner blocks can be of different sizes, that is, the arms thereof may be of different lengths, but the corner blocks are of the same height and 100 105 110

width as the plain blocks 1. The arms of the block 4 illustrated in Fig. 4 are arranged at a right angle relative to one another, but it is evident that the arms of the corner blocks can be arranged at different angles relative to one another, so that various shapes of buildings can be provided for. These blocks are formed of concrete or other suitable plastic material, and may be provided in different colors, to represent terra cotta, brick and the like.

In building up a toy house or other structure, the blocks are laid in courses, as in a regular building, the walls being built up by the judicious use of the blocks 1 and 4. The courses are locked together, so that the structure will be substantial, and this is accomplished in a simple yet efficacious manner by the use of dowel pins 7 of square construction, and preferably formed of wood, although any other suitable material can be used. These pins 7 can be readily inserted downwardly through the openings of the blocks, as the blocks are built up, and if the pins project above the blocks, other blocks can be slipped upon the pins, certain ends of the pins 7 being tapered, as at 8, so that the pins can readily enter the openings, and in order that the pins and blocks can be assembled without trouble. The pins are used at such points, as to lock the different courses together, and the pins may be coated with paraffin or equivalent material to act as a lubricant, whereby the pins can be slipped into and out of the holes of the blocks without sticking. A plurality of alining vertical pins can be used, when the height of the structure is increased, and the adjacent ends of the pins 7 are adapted to bind within certain blocks, since the meeting ends of the pins are chamfered or beveled, as at 9, whereby the pins in being forced together, will cause them to bind at their meeting ends within the respective blocks. Thus, the dowel pins can be extended to different heights, whereby all of the courses are locked together, to prevent the collapse of the building even though it be built to a considerable height. The dowel pins 7 can be of different lengths, and each of them is provided with a longitudinal groove 10 in one side, useful when windows, doors, or other openings are provided in the building.

Where there is a window, door or other opening in the wall of the building, the dowel pins 7 are exposed, the adjacent blocks having their recesses 3 engaging said pins 7, as seen in Fig. 2, so that said pins 7 not only provide the frame members of the window, but also assist in locking the blocks of the different courses in place. The grooves 10 of the window-frame-forming pins 7 face the center of the window, to receive the side edges of a window pane or panel 11, constructed of glass or other suitable material,

and which may be left plain or which may be ornamented. The pane 11 can be slipped downwardly into engagement with the pins 7 during the building up of the structure, and upper and lower frame members 12, constructed of wood, are cemented or otherwise secured to the upper and lower ends of the pane 11. The members or pieces 12 are preferably provided with grooves 13 receiving the ends of the pane 11, and in which the pane is cemented, although the members or pieces 12 can be detachable from the pane if desired. The members 12 are of a length slightly shorter than the width of the pane 11, whereby the edges of the pane 11 can enter the grooves 10, while the members 12 simply fit between and abut against the pins 7. The panes 11 may be of different widths and lengths, according to the standard unit of measurement, and in some cases, if desired, the dowel pins 7 can be secured to the edges of the panes, so that the panes and dowel pins are inserted simultaneously. It is also possible to provide one or more of the dowel pins 7 with opposite grooves. Such a pin is designated at 7', having the opposite grooves 10', where a double window is used, and this permits a series of windows to be provided with a pin 7' between each pair of windows. The opposite grooves 10' receive the two panes 11. Thus, the dowel pins provide the jambs of the windows, doors, and the like. The openings of the blocks of the various courses are all in vertical registration, for the reception of the dowel pins.

Comparing Figs. 2 and 10, it will be observed that the dowel pins 7 may be mounted in different positions, about their axes, so that the grooves 10 in the pins may be disposed inwardly or outwardly with respect to the blocks.

The dowel pin 14 illustrated in Fig. 9 may also be used independently of or in conjunction with the dowel pins 7, this pin 14 being constructed of wood, and being of square or rectangular cross section. The pin 14 is provided with slots 15 cut therein from its opposite ends, whereby the pin is expandable and contractible transversely. Thus, the pin can be compressed to enter the openings of the blocks, and when the pin is released, it will expand to fit tightly within the blocks, whereby to hold the blocks of the superposed courses firmly in place. The pin 14 may be of any suitable length.

From the foregoing, taken in connection with the drawings, it is believed that the invention can be thoroughly understood and its advantageous features appreciated, it being obvious that the present invention enables various sizes and styles of toy buildings to be built up by a child, to provide for the child's amusement and education. The invention is not only useful as a toy, but can also be used for exhibition or display pur-

poses, as a model or reproduction of a full sized building.

If desired, the slots 15 of the dowel pin 14 can be filled with rubber or other compressible material, so that the pin will be more substantial, and less apt to break.

Having thus described the invention, what is claimed as new is:

1. A toy building wall composed of superposed courses of blocks having registering openings, and pins inserted in and removable from said openings to lock the blocks of the various courses together when inserted and to enable the blocks to be separated when said pins are withdrawn, said pins being insertible in different positions about their axes, said wall having an opening therein, one of said pins being located at the side of the wall opening and engaging the ends of the corresponding blocks to hold them in place, said pin extending beyond the wall opening into other blocks to be held in place thereby, and having a groove in one side.
2. A toy building wall composed of superposed courses of blocks having square

openings between their ends and half-openings at their ends, said openings being in registration and spaced according to a standard unit of measurement for the blocks, 30 and pins inserted through said openings to lock the blocks of the various courses together and adapted to be withdrawn from said blocks to enable the wall to be knocked down and the blocks separated for rebuilding, said pins having grooves in one side and being insertible in different positions about their axes, said wall having an opening, two of said pins being disposed at the side of said wall opening, those blocks at the side 40 of the wall opening having their respective half-openings engaging said pin to hold said blocks in place, and said pin entering other blocks beyond the wall opening to be held in place thereby.

In testimony that I claim the foregoing as my own I have hereto affixed my signature in the presence of a witness.

HARMON S. PALMER.
